Attorneys.

UNITED STATES PATENT OFFICE.

GEORGE W. TONEY, OF WALTHAM, MASSACHUSETTS, ASSIGNOR, BY MESNE ASSIGNMENTS, TO OLD COLONY TRUST COMPANY, A CORPORATION OF MASSACHUSETTS, TRUSTEE.

RESETTING MEANS FOR COUNTERS.

Application filed August 16, 1917. Serial No. 186,497.

To all whom it may concern:

Be it known that I, GEORGE W. TONEY, a citizen of the United States, residing at Waltham, in the county of Waltham and State of Massachusetts, have invented new and useful Improvements in Resetting Means for Counters, of which the following is a specification.

The present invention relates to indicators and is designed particularly with reference to odometers for the purpose of resetting the number disks which show the mileage of single trips, but is equally well applicable to all sorts of counters having number-carrying disks adapted to indicate the number of any sort of quantities or operations. It is the object of the present invention to provide a re-setting means which can be operated by one hand of the user for both putting the number disks in condition for re-setting and then re-setting them, and is operative to perform this result without shifting any of the number disks from their normal locations and without disturbing the connection between the unit-indicating disk and the next disk at the left.

The invention consists in the combination hereinafter described and claimed. This combination is shown in connection with a combined odometer and speedometer designed for use with automobiles, and it is especially useful in that relation, but it is not limited thereto, or in any other manner than as indicated by the foregoing statement of the invention and by the appended claims. In the drawings,

Figure 1 is a face view of the instrument referred to.

Figure 2 is a sectional view enlarged on line 2-2 of Figure 1.

Figure 3 is a similar view of the parts wherein my invention particularly resides, such parts being in a different position from that shown in Figure 2.

The same reference characters indicate the same parts in all the figures.

In the drawings 11, 12, and 13 represent disks carrying on their peripheries a series of numerals, of which, in an odometer, the disk 11 usually represents tenths of miles, the disk 12 represents miles and the disk 13 tens of miles; but since in other forms of counters correspondingly arranged

disks indicate other values, and as in an odometer the disks are essentially units, tens, and hundreds-indicating disks, the disk 11, 12, and 13 will be so designated in the following description and claims. These disks constitute the indicator and are arranged, as usual, back of a dial which has an opening through which only one of the figures on each disk is ordinarily visible at one time. The disk 11 is formed in part as, or is connected to, a sleeve 14, which fits in a bushing 15, secured upon a post 16, while the other disks are mounted on a sleeve 17 secured at one end in a support 18 and fitting a drive shaft 19, which latter also passes through an opening in the center of the disk 11, by which it is supported. On the shaft 19 is mounted and secured a collar 20 carrying a gear 21 by which the shaft is driven. Fixed to this shaft within the sleeve 14 is a toothed clutch member 22 which co-acts with a complementary toothed clutch member 23 having sliding engagement with the sleeve 14, and thereby transmitting rotation to the latter and to the unit number disk 11. Clutch member 23 is normally held in engagement with the clutch member 22 by a spring 24. Sleeve 14 is structurally a part of the disk, and may be considered as an elongated hub, having a longitudinal socket large and deep enough to contain the clutch member 23 and the spring 24.

Rotation being imparted to the disk 11 by the means last described, is transmitted step by step to the disk 12, and from the latter to the disk 13 by carrying wheels 25 and 26 which are supported in holders 27, 28, respectively, fixed upon the sleeve 17, and co-operating with gear elements on the hub portions of the several disks in the manner common in intermittent carrying mechanisms used for counting apparatus. As my invention involves no modification in the carrying mechanism I have not attempted to show the construction in detail of that here used, which is simply one of the forms which has already long been in use.

When it is desired to set the number disks in the zero-indicating position, or in any other position for that matter, it becomes necessary to disconnect the clutch members 22 and 23, and to rotate the disk 11, which is then independent of the driving shaft

19, in the desired manner. Both this disconnection and rotation are accomplished by manipulation of a setting crown 29 which is mounted upon a stem 30 occupying a 5 bearing in a bracket 31 which extends outward from the case of the instrument, and is preferably so arranged that the crown 29 projects slightly beyond the plane of the face of the instrument and its axis is approximately 10 perpendicular to such plane. Stem 30 is movable endwise and is normally held to the limit of its outward movement, that is the position shown in Figure 3, by a spring 32 which surrounds the stem 15 within the socket containing the latter and bearing against a shoulder 33 on the stem as shown. The stop which limits outward movement of the stem is constituted by the hub of a gear element 34 which is secured 20 to the stem by a pin 35.

The gear element 34 meshes with a complementary gear element 36 which is secured by a screw stud 37 to the sleeve or hub 14 of the disk 11, whereby rotation of the stem 25 is adapted to rotate the disk when the clutch is disconnected. Within the hub 14 and passing through the gear 36 is a pusher 38 having its outer end beveled and its inner end formed as a shell which passes over 30 the clutch member 22 and bears against a shoulder 39 on the clutch member 23, the said pusher being adapted when pushed inward, that is to the left with respect to the drawings, to displace the clutch member 23 35 against the yielding resistance of the spring 24, and thus disconnect it from the member 22. The beveled end of the pusher contacts with a complementary bevel or cone portion 40 on the end of the stem 30 passing 40 beyond the gear 34.

In the normal position of the parts, which is that shown in Figure 3, the setting stem and its crown are pushed outward, and so also is the pusher 38; the clutch 22, 23 being 45 then connected, and the gears 34 and 36 being partly in mesh, or at least sufficiently so to be guided into complete mesh when the stem is displaced. It is not necessary, however, that the gears should mesh at this 50 time, for the invention is equally operative in a combination in which the gears are out of mesh in the normal position, but are sufficiently pointed to slip correctly into mesh when brought together.

55 Now when it is desired to re-set the indicator, the crown is pushed inward and is then turned. The first, or endwise movement of the stem so produced causes the beveled end 40 of the stem to slide upon 60 and push back the beveled end of the pusher, thereby disconnecting the clutch. At the same time the gears are brought into mesh if they were not previously in mesh, and rotation of the crown then turns the stem, 65 in either direction, according to the direc-

tion of rotation of the crown. Disk 11 is thus directly turned, and movement is transmitted therefrom to the other disks, as in the usual operation, through the carrying mechanisms. On account of the necessity 70 of the stem and pusher to engage properly in all positions, their beveled ends are made of conical form, either as tapered points or frusta of cones.

A new result of special importance accomplished by the herein described mechanism is that, not only is the re-setting mechanism put in condition for operation by manipulation of the device which re-sets the indicator, but this result is accomplished 75 without shifting the unit-indicator and therefore without breaking the connection between the same and the next indicator, whereby it is impossible for this or any other of the disks to become displaced from 80 its correct relation to the others. The importance of this result resides in the fact that in mechanisms of the sort in which disconnection of the unit disk from the driving shaft is made by shifting the disk bodily, 85 the connection between this disk and the next one of the series is broken and it becomes possible then to so place the tens disk upon re-connecting it with the next one, that the number which it presents to 90 view is out of the line with the exposed numbers of the other disks. Such disalignment of any of the disks is impossible in 95 the combination here described.

What I claim and desire to secure by Letters Patent is:

1. An indicator comprising a series of rotatable number disks, a driving shaft, a clutch element associated with said shaft, a complementary clutch element having a sliding but non-rotative engagement with the units disk of said series, a shifter engaged with said complementary clutch element and protruding from one end of said series and having an inclined impelling surface, said complementary clutch element and shifter being arranged to effect uncoupling of the clutch by inward movement of the shifter, an endwise and rotatably movable setting stem arranged at an angle to the axis of said 105 disks having a part arranged to act on the impelling surface of the shifter for causing uncoupling of the clutch elements when moved in one direction, and transmission 110 gearing between said setting stem and said units disk operable at such time to effect rotation of said units disk when the stem is rotated.

2. The combination with number-exhibiting disks and a drive shaft, of a clutch member connected to said drive shaft, a complementary clutch member connected to said unit disk in a manner permitting axial 115 displacement, a rotatable and endwise movable setting device, intermeshing gears con- 120 125 130

nected to said device and said unit disk for rotating the latter when the setting device is rotated, and a pusher engaged with said device and movable by endwise movement 5 thereof to disconnect the second named clutch member from the first named clutch member.

3. The combination with a number-exhibiting counter disk and a drive shaft, said 10 disk being relatively immovable axially of the shaft, of a clutch member connected with said disk and movable axially thereof into and out of connection with the shaft, an actuator engaged with said member for so 15 moving it, a setting device extending at an angle to said drive shaft and having means for moving said actuator thus to shift said clutch member, and mechanism by which said setting device is operable at the same 20 time to rotate said disk.

4. In a counter the combination with a number-exhibiting disk of a driving shaft passing through said disk and carrying a clutch member adjacent to the end thus passing 25 through, a complemental clutch member between said clutch member and the disk movable axially of the shaft into and out of engagement with the first clutch member and having rotation-transmitting connection 30 with the disk, a pusher constructed as a shell passing over the first named clutch member into engagement with the second clutch member, having an exposed tapered surface and being movable endwise, an end- 35 wise movable setting stem having a tapered surface engaged with the tapered surface of said pusher, and gear elements connected

to said stem and disk, respectively, adapted to be intermeshed for rotating the disk by rotation of the stem. 40

5. A rotatable number indicator, a shaft, a clutch element on said shaft near its end, a complemental clutch element on said shaft more remote from its end than the first clutch element connected to said number indicator but being movable longitudinally of the shaft, a clutch actuator embracing and passing the first clutch element being engaged with the second clutch element, a rotatable and axially displaceable 45 setting device and gearing carried by said setting device and number indicator for transmitting rotation from the former to the latter, the setting device and clutch actuator having adjacent complemental contacting surfaces disposed to cause disengagement of the clutch members by said actuator 50 when the setting device is so displaced. 55

6. In a counting mechanism having a series of related counter disks, a shaft coaxial therewith for driving the same, a discon- 60 nectible clutch between said shaft and the units disk of said series, a clutch discon- 65 nector separate from the shaft arranged coaxially with the disks and having an accessible protruding end, being adapted to disconnect said clutch when its protruding end is pushed inwardly, and means for so moving said disconnector whereby to make the units disk free for independent rotation and re- 70 setting. 75

In testimony whereof I have affixed my signature.

GEORGE W. TONEY.
